Patented Jan. 9, 1900.

I. E. PALMER.
HAMMOCK SUPPORT.

(Application filed June 26, 1899.)

(No Model.)

UNITED STATES PATENT OFFICE.

ISAAC E. PALMER, OF MIDDLETOWN, CONNECTICUT.

HAMMOCK-SUPPORT.

SPECIFICATION forming part of Letters Patent No. 641,033, dated January 9, 1900.

Application filed June 26, 1899. Serial No. 721,911. (No model.)

To all whom it may concern:

Be it known that I, ISAAC E. PALMER, a citizen of the United States, and a resident of Middletown, in the county of Middlesex and 5 State of Connecticut, have invented a new and useful Improvement in Hammock-Supports, of which the following is a specification.

My invention relates to certain improvements in hammock-supports, one object being 10 to provide a hammock-support in which the backbone or ridge-pole is made extensible and contractible, so that the said support may be conveniently packed for shipment and when set up for use may be extended to suit the 15 wish of the occupant of the hammock supported by it.

A further object is to provide an effective means for rigidly clamping the legs of the support to the ends of the ridge-pole.

20 A still further object is to provide metallic brackets for the several parts, which may be clamped rigidly thereto without the use of bolts.

25 A practical embodiment of my invention is represented in the accompanying drawings, in which—

Figure 1 is a view of the support in end elevation as it appears when set up for use, the 30 position of the legs when released from their clamping engagement with the ridge-pole for permitting the legs to be removed from the ridge-pole being shown in dotted lines. Fig. 2 is a view of the support in side elevation, the support being shown in an extended position in dotted lines. Fig. 3 is a partial top 35 plan view of the support. Fig. 4 is an enlarged detail end view showing the manner of clamping the legs to the ridge-pole. Fig. 5 is a detail sectional view with the parts in 40 the same position as in Fig. 4. Fig. 6 is a view similar to Fig. 4, showing the position of the parts when the legs are swung away from each other for releasing them from engagement with the ridge-pole to permit the 45 legs to be removed therefrom. Fig. 7 is a side view of the parts shown in Fig. 4. Fig. 8 is an enlarged detail front view of the device for clamping one of the extensible sections of the ridge-pole to the middle section. Fig. 9 is a 50 transverse vertical section through the same. Fig. 10 is a transverse vertical sectional view through the middle section of the ridge-pole,

showing the bracket for rigidly spacing the side bars of the section apart. Fig. 11 is a top plan view of the same; and Fig. 12 is a view 55 of the inner end of one of the extensible sections, showing the bracket for rigidly spacing the top and bottom bars apart.

The backbone or ridge-pole of the support is composed of a middle section *a* and two extensible end sections *b* and *c*. The middle section *a* comprises two longitudinal side bars, which are rigidly spaced apart at a point about midway their lengths by a bracket *d*, which bracket has two vertical portions *d'* *d''*, 60 which extend along the inner sides of the side bars, top and bottom webs *d³* *d⁴*, which connect the vertical portions, and top and bottom extensions *d⁵* *d⁶* and which embrace the top and bottom edges of the side bars lay over 65 their outer sides. The side bars of the middle section are rigidly secured together at all times only by the bracket *d*. One of the said side bars is provided with a longitudinal central rib *d⁷*, which extends inwardly along its 70 inner side opposite to a similar rib *d⁸*, extending along the inner side of the other side bar. 75

Each of the extension end sections *b* and *c* consists of top and bottom longitudinal bars spaced apart at both ends, which bars are 80 fitted to slide along within the middle section *a* of the support, the longitudinal ribs of the said middle section serving to guide the extensible section in its inward and outward movements. The inner ends of the longitudinal top and bottom bars of the extensible section are rigidly spaced apart by means of 85 a bracket *e*. The bracket *e* is provided with a vertical web which extends inwardly, which web is adapted to be driven into the ends of 90 the two bars. The bracket *e* is further provided with pairs of laterally-extended wings, which are fitted to embrace the top and bottom edges of each of the bars, which wings are preferably caused to impinge the wood of 95 the said bars, so as to hold them rigidly in position.

The outer ends of the top and bottom bars of each of the extensible sections are rigidly spaced apart by means of a bracket *f*, which 100 bracket has an inwardly-extended vertical web *f'*, which is fitted to be driven into the ends of the said bars. The bracket *f* is further provided with a pair of inwardly-ex-

tended branches $f^2 f^3$, fitted to embrace the top bar, and a pair of branches $f^4 f^5$, fitted to embrace the bottom bar of the extensible section. The opposite edges of the several branches are preferably serrated to form teeth, which teeth are bent into the wood of the bars, so as to securely clamp the bracket in its position without the use of bolts. The spacing-bracket f is further provided between the upper and lower branches with two pairs of seats $f^6 f^7$, one pair of seats— f^6 , for instance—being located at the outer end of the bracket and the other pair of seats f^7 being located at the inner end of the said bracket. The bracket is further provided at the inner end of its lowermost branch f^5 with a downwardly-extended lug g for preventing the supporting-legs from being shoved too far inwardly from the ridge-pole. The means which I employ for clamping the extensible sections of the ridge-pole to the middle section in any desired longitudinal adjustment consist of fastening devices located at the ends of the said middle section, each of which clamping devices is composed of the following parts: A clip h is secured to the outer side of one of the side bars of the middle section near its end and a second clip i is secured to the outer side of the opposite side bar at a point opposite to the clip h . A screw-bolt j passes through the clips h and i and the side bars, the head of the bolt being engaged with the outer face of the clip h , for instance, and its screw-threaded end projecting beyond the outer face of the clip i . The screw-threaded end of the said bolt j is engaged by a clamping-nut k , which nut is preferably provided with an operating-handle, so as to permit a considerable purchase to be obtained by the operator upon the said nut for causing the nut to draw the side bars of the middle section snugly into engagement with the top and bottom bars of the extensible section when the nut is screwed home. As the nut k is unscrewed the extensible section will be released and may be slid longitudinally to the point desired, when it may be again clamped. The ridge-pole is supported by four legs, arranged in pairs at its opposite ends. As the two pairs are alike, I will only describe the legs l and m at one end of the support. Each leg consists of a bar split from its upper end a considerable portion of its length. The leg may be made of a single piece, or it may be made of separate pieces secured firmly together. A bracket n is provided with a pair of inwardly-extended branches $n^1 n^2$, fitted to embrace one of the bifurcated ends of the leg l , and another pair of branches $n^3 n^4$, arranged to embrace the other of the bifurcated ends of the leg l . A web n^5 connects the branches $n^1 n^2$ of the said bracket. A bracket o , quite similar to the bracket n , is provided with two pairs of branches $o^1 o^2 o^3 o^4$, which are arranged to embrace the bifurcated ends of the leg m . This bracket o is also provided with a web o^5 for connecting the branches $o^1 o^2$.

The edges of the several branches of the brackets n and o are preferably serrated to form teeth, which are caused to impinge the wood of the supporting-legs, so as to rigidly secure the supporting-legs within the brackets without the use of bolts.

The brackets n and o are hinged to inner and outer collars p and q by hinge-pintles r and s , which collars are fitted to slide loosely over the end of the ridge-pole until they are stopped by the engagement of the collar p with the lug g , carried by the bracket f .

The brackets n and o are provided with pairs of inwardly-extended shoes t and u , which are adapted to engage the seats in the bracket f and grip the collars p and q rigidly to the ridge-pole when the legs are drawn inwardly toward each other. When the legs are swung outwardly away from each other, the pairs of shoes t and u are swung away from their engagement with the seats, and the collars p and q are thereby released, permitting the pair of legs to be removed from the ridge-pole.

The leg-brackets n and o are provided on their branches $n^4 o^4$ with lugs $n^6 o^6$, arranged to limit the outward-swinging movement of the legs l and m by their engagement with the collar q .

The pairs of legs are locked in their position nearest to each other for clamping the legs rigidly to the backbone by a link connection, which is composed of a pair of rods $w w'$, hinged together, the rod w being hinged to a gripping device x , fitted to slide along the leg l , and the rod w' being hinged to a gripping device fitted to slide along the leg m . As the gripping devices x and y are slid upwardly the legs l and m may be swung away from each other, thus permitting the removal from and insertion of the legs onto the ridge-pole. This link connection $w w'$ will permit the legs to be folded closely together when not in use.

One of the collars, in the present instance the collar q , is provided with a suitable hook z for the attachment thereto of one end of a hammock.

The support as above constructed is very simple and strong, is composed of a very few parts, is quickly adjustable, and readily set up or taken down.

The several metallic parts hereinbefore described may be made of some malleable metal, so as to permit them to be firmly secured in their respective places.

This construction enables me to do away entirely with the use of bolts for clamping the several parts of the woodwork of the support together.

While I have described my improvement as a hammock-support, it is obvious that the structure may be used as a support for a chair or swing, if so desired.

What I claim is—

1. The combination with a ridge-pole, of

supporting-legs, means for hinging the members of a pair of supporting-legs on the ridge-pole in position to swing toward and away from each other to grip and release the ridge-pole and means for holding the legs in their closed adjustment, substantially as set forth.

2. The combination with a ridge-pole, and collars arranged to loosely embrace the ridge-pole, of supporting-legs hinged to the collars to swing into and out of gripping contact with the ridge-pole and means for holding the legs in their closed adjustment, substantially as set forth.

3. The combination with one of the end sections of a ridge-pole comprising top and bottom bars, of a bracket for rigidly spacing the top and bottom bars apart at their outer ends, the said bracket being provided with seats, a collar arranged to loosely embrace the top and bottom bars and a pair of legs hinged to the said collar, the said legs being provided with brackets having inwardly-extended shoes adapted to engage the said seats for clamping the legs to the end section, substantially as set forth.

4. In a hammock-support, an end section of the ridge-pole comprising top and bottom bars, a bracket for rigidly spacing the inner ends of the top and bottom bars apart and a second bracket for rigidly spacing the outer ends of the top and bottom bars apart, substantially as set forth.

5. The combination with a ridge-pole and supporting-legs arranged in pairs, of means for hinging the members of a pair of supporting-legs on the ridge-pole to swing into and out of gripping contact and means for bodily adjusting a pair of supporting-legs toward and away from another pair of supporting-legs without removing them from the ridge-pole, substantially as set forth.

6. A backbone for a hammock-support, comprising a middle section, two extensible end sections, the middle section consisting of two side bars rigidly spaced apart about midway their length, for receiving between them the end sections and means for drawing the side bars into binding contact with the end sections in different longitudinal adjustments, substantially as set forth.

7. A backbone for a hammock-support comprising a middle section and two extensible end sections fitted to be clamped thereto, each end section comprising top and bottom bars rigidly spaced apart at their opposite ends, substantially as set forth.

8. A backbone for a hammock-support comprising a middle section and two extensible end sections, the middle section comprising two side bars rigidly spaced apart at a point

intermediate their ends and having longitudinal ribs on their inner faces, and the end sections each consisting of top and bottom bars fitted to be guided in their inward and outward sliding movements by the said ribs 65 on the middle section, substantially as set forth.

9. A backbone for a hammock-support comprising a middle section and end sections, the middle section comprising two longitudinal 70 side bars and a bracket for spacing the side bars rigidly apart at a point intermediate their ends, said bracket having two vertical portions extending along the inner sides of the side bars, a web connecting the vertical 75 portions, and top and bottom extensions which embrace the top and bottom edges of the said side bars, substantially as set forth.

10. The combination with the middle section of the backbone of a hammock-support, 80 said middle section comprising two side bars, and an end section fitted to slide between the said side bars, of a clamping device for securing the two sections together, consisting of clips secured to the outer sides of the two 85 side bars of the middle section, a screw-bolt passing through the clips and side bars, said bolt having its head engaged with one of the clips and its screw-threaded end projecting through the other clip, and a clamping-nut 90 engaging said screw-threaded end, substantially as set forth.

11. The combination with a backbone, a collar fitted to loosely embrace the end of the backbone, swinging legs hinged to the said 95 collar in position to engage the backbone when swung toward each other for clamping the legs to the backbone and stops carried by the legs in position to engage the collar for limiting the outward swinging movements of the 100 legs, substantially as set forth.

12. The combination with a backbone and a collar arranged to loosely embrace the end of the same, a pair of swinging legs hinged to the collar in position to engage the backbone when swung toward each other and means for holding the legs in their closed adjustment comprising a pair of gripping devices arranged to slide along the legs and a flexible connection between the gripping devices, substantially as set forth.

In testimony that I claim the foregoing as my invention I have signed my name, in presence of two witnesses, this 17th day of June, 1899.

ISAAC E. PALMER.
